BOBBIN WINDER

James Armenti, Maplewood, N. J.

Application October 6, 1947, Serial No. 778,060

2 Claims. (Cl. 242—22)

1

This invention relates to bobbin winders and more particularly to those used in conjunction with sewing machines of the factory type.

In factory use of sewing machines, it is common practice to locate the same on one long bench or table, and rather close to each other to conserve space. Thus the needle end of one machine is often a foot or so away from the drive end of the next machine, and work, if at all bulky, encroaches from the needle end of one machine on the table to the head end of the next machine. Furthermore, in factories using sewing machines it is a prevailing practice to employ operators on a piece-work basis, and interference of the work of one operator with operation by another has to be avoided. Each operator has to wind or fill her own bobbins as required, and it is usual to have a bobbin winder at the head end of each machine. To avoid delays, an operator keeps the bobbin winder threaded ready for use, and therefore resents having that thread disturbed by an adjacent operator, inadvertent though it may be, as by the work of the adjacent operator catching and dislocating the bobbin thread. Also, since time consumed winding a bobbin is lost time to the remunerative productive time for an operator, the winding of the bobbin is done at high speed. It therefore becomes essential to automatically stop the bobbin from winding when it is full, since in only a matter of moments the bobbin otherwise becomes overloaded and convolutions of the thread will slide over the end flanges of the bobbin and become snarled. Yet a bobbin should be wound as full as possible so as to reduce the number of times a day that the operator has to stop to wind it.

This invention seeks improved means for saving time of the operator in bobbin winding.

More specifically, an object of the invention is to provide improved means for setting a bobbin winder in motion and to stop the winding when the bobbin is loaded.

Another object is to simplify and reduce operations required by the operator for winding a bobbin to loaded condition.

A further object of the invention is to provide a single lever to function as the operator-controlled starting means and as the automatic load-gauging means.

Yet another object of the invention is to provide a control lever also operable by the operator for manual manipulation to stop the winding of the bobbin if necessary prior to automatic operation thereof.

Again, an object of the invention is to both

2

afford ready access to the bobbin winder by the operator and protection against disturbance thereof between bobbin-winding operations.

Other objects and advantages of the invention will appear hereinafter to those skilled in the art to which it apertains both by direct reference thereto and by implication from the context as the description proceeds.

Referring to the accompanying drawings in which like numerals of reference indicate the same or similar parts throughout several views:

Figure 1 is a front elevation of the drive end of a sewing machine with my improved bobbin winder associated therewith and shown in front end elevation;

Figure 2 is a side elevation of the bobbin winder looking from right to left of Fig. 1, and with part of the hinged guard broken away for showing parts otherwise behind the same;

Figure 3 is a fragmentary side elevation looking in the same direction as in Fig. 2 and showing the bobbin winder in its idle position; and

Figures 4 and 5 are sectional views on lines 4—4 and 5—5 respectively of Fig. 2.

In the specific embodiment of the invention illustrated in said drawings, the reference numeral 10 designates the usual bench or table top on which a sewing machine 11 is secured, said sewing machine having the usual driving

30 pulley 12 and clutch release 13 and driving belt 14. It will be understood that the clutch release is a common feature of present-day sewing machines which enables the driving belt 14 and machine pulley 12 to operate when winding a bobbin without simultaneously driving the usual sewing mechanisms. The belt is in turn driven by a motor (not shown) or other impelling mechanism, as usual, located below the table. The

front reach of the driving belt is usually operated 35 in a downward direction and will be so considered herein but without imposing limitation in that respect.

The bobbin winder provides a drive wheel 15 arranged in a vertical plane defined by the front and back reaches of the belt; that is to say, is

40 in the plane of the belt and the plane of the belt is perpendicular to the axis of the machine pulley 12. Said drive wheel 15 of the bobbin winder is in front of the front reach of the belt

45 and in idle position is out of contact from said belt, but for operating purposes is mounted to be swung toward and into engagement with the said belt.

The bobbin winder furthermore provides a

50 housing 16 here shown as sheet metal and hav-

55 ing

ing a base 17 secured to the table and having an up-standing flange or side wall 18 toward the sewing machine and extending in a forward-rearward direction with respect thereto or parallel to the aforesaid plane of the driving belt. Said belt passes between the sewing machine and said upstanding flange and the base extends in a direction away from both the flange and belt.

Above the base, near the front end of the same is provided an upwardly directed rocker arm 19 the lower end of which has hinged mounting upon a fixed stud 20 projecting in a perpendicular direction from said flange or side wall 18 of the housing 16. The rocker arm therefore is adapted to be swung in a forward-rearward direction. At an upper part of said rocker arm there is rotatably carried a rotatable shaft 21, said shaft being parallel to the stud 20 and projecting at both ends thereof from the sides of said rocker arm. At the side of the rocker arm toward the housing flange, said shaft projects through said flange and on the opposite side of the flange from the rocker arm carries said drive wheel 15 which is fixed thereon so that rotation of the drive wheel effects a corresponding rotation of said shaft. Said shaft passes through an arcuate slot 22 in the flange, said slot having its center of curvature at the center of stud 20 thereby permitting the desired swing or oscillation of the rocker arm and rotatable shaft. The amplitude of oscillation for the rocker arm and shaft is adequate to advance the driving wheel in a rearward direction into depressing engagement with the front reach of the driving belt and to retract said wheel in a forward direction from engagement with said belt. This retracted or forwardly swung location of the rocker arm and driving wheel is referred to herein as the idle position thereof. Said shaft is suitably shouldered and retained from longitudinal movement in its assembled position, for which purpose the end of the shaft protruding from the rocker arm away from the wheel-supporting end is shown as having a peripheral boss 23 next to the rocker arm of larger diameter than the rest of the shaft. This and spacing collar 24, are carried on the shaft between the rocker arm and flange and between the flange and wheel, and the wheel is secured in place on the shaft by a set-screw 25.

Said protruding end of the shaft having boss 23 terminates with a diameter less than that of the boss and constitutes a bobbin-supporting mandrel of proper diameter to fit within the usual central hole of the bobbin to be wound. In order that the mandrel may frictionally engage the bobbin, a longitudinal slit 26 is provided in that part of said shaft which constitutes the mandrel thereby enabling the resultant segments of the mandrel on opposite sides of the slit to be sprung resiliently toward each other sufficiently to permit a bobbin 27 to be slid onto the mandrel and be frictionally held thereby. Boss 23 accordingly not only functions to prevent longitudinal displacement of the shaft, but also acts, at its other end, to limit the inserted position of the bobbin.

A lever and toggle mechanism is provided for swinging the rocker arm. As shown, this mechanism provides a lever 28 which swings in the same general direction as the rocker arm and is mounted upon and rotatable with a stud shaft 29 located parallel to the mandrel and to the hinging of said rocker arm. Said stud shaft is

rotatably carried in and crosswise of the rocker arm at a part thereof intermediate of the hinging of said arm and the first described or bobbin-carrying shaft. Said lever is at the same side of the rocker arm as the mandrel end of said bobbin-carrying shaft, and at the other side protrudes to support a toggle arm 30 fixed thereon and extending forwardly therefrom. The forward end of said toggle arm is pivotally connected by stud screw 31 or other means to the rear end of a toggle link 32 the forward end of which is pivoted, as by stud screw 33 or other means to the housing flange. A lip or other stop 34 is provided, as upon the forward under edge of the toggle arm 30 to engage the toggle link 32 for limiting upward swing of said toggle arm and link to a position slightly beyond dead center. Collectively, the toggle arm and link are herein referred to as a toggle, and the described position slightly beyond dead center of the arm and link as shown in full lines in Fig. 2 is referred to as the straightened or holding position of the toggle, whereas the downwardly swung position as shown in Fig. 3 is referred to as the released or broken position of the toggle. By swinging lever 28 rearward, the toggle is straightened to its holding position and in assuming that position necessitates a rearward swing of the rocker arm 19 to transpire, thereby causing drive wheel 15 to engage the sewing machine belt.

Lever 28 is located with respect to the bobbin and has angular disposition with respect to the toggle such that it can be swung partly into the bobbin as shown in Fig. 2 when swinging the toggle to holding position. An upper end of said lever extends above the bobbin at that position of the lever and constitutes a finger hold by which the operator may manipulate the lever without having to touch the bobbin. The distance of swing away from the bobbin as indicated by dotted lines in Fig. 2 to bring the toggle past dead center from holding position thereof, is set to correspond precisely to the diametric size of the bobbin end flanges. Holding position of the toggle is maintained in the position of the lever within its segment of oscillation for all chordal positions of the lever up to its tangential position with respect to the bobbin periphery. As the thread loads the bobbin, it engages the under side of the lever and therefore when the load of thread attains the diameter of the bobbin end flanges the lever is then at its tangential position with respect to the bobbin periphery and has swung the required amount to pass the toggle beyond its dead center position in breaking direction. A spring 20, shown as located upon the rocker arm stud 20 and under suitable actuating tension against the rocker arm, snaps the arm forward to release the driving wheel from contact with the machine belt and thus stops further rotation of the bobbin. A bumper or stop 35 is shown carried by a bracket 36 on the housing flange, located in the oscillatory path of forward movement of the driving wheel, and thus the wheel is both limited in forward swing to idle position and is braked by said bumper so that rotation ceases forthwith.

At the rear end of the housing 16, fixed on base 17 thereof is a standard socket 37 for reception and support of a standard 38 which in turn carries a spool rack 39, spools of thread 40 and thread guide 41.

Likewise at the rear end of the housing 16 and carried by the side flange 18 thereof, is a

thread tensioning means 42 comprising discs 43, 43 on a common stud and of which the outer one is pressed toward the other by spring 44 adjustably as to tension exerted on the thread passing between the discs. Said flange also is shown provided with a rack 45 for extra bobbins.

In order to protect the bobbin winding mechanism and the thread thereto and the spare bobbins from disturbance by work in an adjacent machine, or other interfering factors, a 10 guard 46 in the nature of a swinging door is provided but hinged as at 47 at its lower edge to swing from an upright protecting position to a downward or open position with the guard then substantially flat on the table. This enables an operator to readily open the guard to its position for full access to the bobbin winding mechanism and with least interference with the work of the adjacent operator. Crosswise of the base 17 of the housing there is preferably provided an upwardly tensioned leaf spring 48 the free end of which passes under the guard 46. A contact ledge 49 is provided on the inner side of the guard over the leaf spring and serves to releasably hold the guard in its closed position by the flatwise contact of the spring with the ledge.

I claim:

1. A bobbin-winding mechanism comprising a rotatable wheel, shaft and mandrel rotatable as 30 a unit, said mandrel adapted to mount a bobbin thereon to be wound, a support for said shaft, said support being hinged for oscillatory movement, a toggle attached to and for releasably holding said support at one end of its oscillatory 35

movement, means for operating said toggle, and a housing carrying said mechanism, said mandrel, shaft support, toggle and toggle operating means being within and protected by said housing.

2. A bobbin-winding mechanism comprising a rotatable wheel, shaft and mandrel rotatable as a unit, said mandrel adapted to mount a bobbin thereon to be wound, a support for said shaft, said support being hinged for oscillatory movement, a toggle attached to and having a position for releasably holding said support at one end of its oscillatory movement, and a lever for operating said toggle, and a housing carrying said mechanism, said mandrel, shaft support, toggle and toggle operating means being within and protected by said housing, and said shaft projecting through one side of the housing and having said rotatable wheel on the projecting end of said shaft outside the housing.
